UNITED STATES PATENT OFFICE

ADOLPH M. AUGSTEIN, OF GREAT NECK, NEW YORK, ASSIGNOR TO S. AUGSTEIN & CO.,
A COPARTNERSHIP, OF NEW YORK, N. Y.

DESIGN FOR A KNITTED FABRIC

Application filed December 8, 1928. Serial No. 29,163. Term of patent 3½ years.

To all whom it may concern:

Be it known that I, ADOLPH M. AUGSTEIN, a citizen of the United States of America, and a resident of the town of Great Neck, Long Island, county of Nassau, State of New York, have invented a new, original, and ornamental Design for a Knitted Fabric, of which the following description, in connection with the accompanying drawing, is a specification.

The drawing is a plan view of a piece of knitted fabric embodying my design, the unit shown being repeated in regular succession throughout the length of the fabric.

I claim as my invention:

The ornamental design for a knitted fabric, substantially as shown and described.

ADOLPH M. AUGSTEIN.
